STUDIO COUCH

Martin Fox, Chicago, Ill., assignor to The Seng Company, Chicago, Ill., a corporation of Illinois

Application October 9, 1936, Serial No. 104,795

3 Claims. (Cl. 5—21)

This invention relates in general to a folding bed of the studio couch type in which there is a rigid mattress supporting section supported by legs and open at the front to receive a foldable

5 section carrying a mattress and movable to raise its mattress supporting section to the level of the stationary one.

An important object of the invention is in the provision of mattress supporting frames connected together for parallel movement and extensible into alignment to form a bed.

A further object of the invention is in the provision of an improved raising and mattress supporting means on the movable section.

15 A still further object is in the provision of metal frames for a studio couch construction which are adapted to fold together compactly so that the structure will not be objectionably high when used as a seat, at the same time to 20 provide for mattress sections of sufficient thickness so that they will be comfortable when the sections are extended into alignment to form a bed.

Other objects of the invention will appear hereinafter, the accompanying drawings illustrating a preferred embodiment of the invention, in which

Fig. 1 is a perspective of the metal frame structure in accordance with the invention;

30 Fig. 2 is an end view of the structure in folded condition showing mattress sections carried by the frames; and

Fig. 3 is an end view of the movable structure in partially raised position.

35 Studio couches are usually composed of mattress sections carried by supporting frames. If both mattress sections are carried by the fixed frame an objectionably high seat is provided, and if one of the mattress sections is carried by a movable section the fixed seat frame must be sufficiently high to house the movable frame and a mattress section below it. The present invention overcomes these objections by providing a foldable frame which collapses flatly or close to 40 the floor so that a mattress section of considerable thickness may be supported by it and still will slide freely below the fixed frame.

45 Referring now more particularly to the drawings the fixed mattress support comprises a top marginal frame 5 supported by front and rear legs 6 and 7 and the rear legs connected near their lower ends by a cross brace 8. Within the frame 5 a flexible mattress supporting fabric 9 of any suitable structure is yieldingly supported 50 in a well known manner by helical springs 10.

The mattress supporting frame thus provided is open at its front to receive the movable mattress supporting section which is slidable beneath it.

The movable mattress supporting section comprises end members 11, a front rail 12, and a rear rail 13, all rigidly connected together with vertical supports 14 attached at the front corners for supporting a front board 15. This movable frame is supported at the bottom by castors or 10 rollers 16 and connecting the rear rail 13 and the rear rail 8 of the fixed section are crossed levers 17 and 18 having a central pivot 19 and each lever connected having a fixed pivot 20 at one end and a sliding pivot 21 at the other end to provide a 15 parallel motion guide for the movable frame. This keeps the frames in alignment and the engagement of the sliding pivots 21 at the end of their slots 22 limits the outward movement of the movable frame. 20

25 Mounted in the movable frame is a raisable mattress supporting frame 23 having a flexible mattress supporting fabric 24 secured within the frame by helical springs 25, and the opposite sides of the frame being connected by cross pieces 26 which prevent the bowing or spreading of the rails to which they are connected due to a weight or undue tension of the mattress supporting fabric. 25

30 This mattress supporting frame 23 is supported at its ends and at the outer side by parallel motion devices each comprising a pair of crossed levers 27 and 28 connected together intermediate their ends by a pivot 29. The cross levers at the ends have fixed pivots 30 attaching 35 them to the upper and lower frames and pivots 31 slidable in frame slots 32. The parallel motion device of the front side has fixed pivots 33 and pivots 34 slidable in slots 35 in brackets 36 attached to the upper and lower frames. 40

35 In order to raise and lower the mattress supporting frame 23 a hand lever 37 is pivoted at its lower end 38 at each end of the bottom frame and these levers are cross connected at their pivots by a bar 39 rotatable at its ends in the 45 frame which forms pivots for the levers. Extending from each hand lever 37 is a plate 40 carrying a pivot 41 at one side of the lever to which one end of an operating bar 42 is pivoted, the other end of the bar being connected to the 50 pivot 31 of the cross lever 27 which is slidable in the lower frame slot 32. A spring 43 also connected to the lower end of the cross lever 27 at one extremity and to the rear cross rail 13 at its other extremity tends to draw the crossed 55

levers 27 and 28 in a direction to raise the upper frame 23, at which time the pivots 31 will also engage the ends of the slot 32.

Projecting from each hand lever 37 near the pivoted end is a fixed stop 39 and projecting from its crossed lever 28 is a rigid bracket 39a adapted to engage the stop 39 and to limit the rearward or raising movement of the levers 37. In this stop position the frame 23 is at its proper height and the sliding pivots 31 of the levers 27 are held at the ends of the slots 32.

In order to lock the upper frame in its raised or lowered position the pivot 41 carried by the plate 40 is moved by the lever 37 below the line joining the pivots 31 and 38 and when in the lowered position as shown by Fig. 2, the free end of the hand lever is below the line joining the pivots 31 and 38 so that in either position it is necessary to manually operate the hand lever in order to change the position of the upper frame 23.

In its raised position the frame 23 is thus locked against movement in either direction and can only be released and lowered by manual operation of the connected levers 37. When the frame 23 is in its lowered position a manual lifting of the frame itself may be sufficient to overcome the locking of the frame in its downward position as shown in Fig. 2, in which case the springs 43 will carry the locking lever over to its upper locking position as shown in Fig. 1.

When in actual use a mattress section 44 rests upon or is secured to the raisable frame 23 and a mattress section 45 rests upon or is secured to the fixed supporting frame 5. These mattress sections are preferably separate and of the same height or thickness so that when the mattress supporting sections are moved into alignment, they will form a bed of uniform thickness and uniform resiliency.

When not in use as a bed the raisable section is depressed or lowered by means of the hand levers 37, the parallel motion supports at the front and ends hold the movable and raisable frames in alignment, and the movable frame is then rolled under the fixed frame 5 where the height of this frame from the floor is sufficient to house the movable frame structure and also the mattress section 44 carried by it. This provides a studio couch structure which is not too high from the floor even though a mattress section of considerable thickness is applied to the fixed frame, the fixed frame may be entirely enclosed and upholstered at the sides and back, leaving the front open, and the front is closed by the front board 15 which may also be suitably covered or upholstered to form a neat appearing and attractive article of furniture.

I claim:

1. In a studio couch, a collapsible section having a lower frame and a raisable upper frame connected by opposite pairs of crossed levers pivoted intermediate their ends, each lever having a fixed pivotal connection at one end with one frame, and a pivoted and sliding connection at the other end with the other frame; an operating lever pivoted to the lower frame between the

pivotal and sliding connections of the crossed levers with the frame and having a plate fixed to the lever and pivoted to a link connecting it to that end of the lever which has a pivoted and sliding connection with the lower frame for raising and lowering the upper frame; the pivotal connection of the link with plate of the operating lever being at one side of the pivotal connection thereof to move it past a connecting center line between the pivotal connection between the other end of the link and the pivoted end of the lever, and stop means carried by the adjacent crossed lever for engaging stop means on the operating lever and limiting its movement in one direction so that the upper frame is locked fixedly in its raised position.

2. In a studio couch, a collapsible section having upper and lower frames connected by opposite pairs of crossed levers, each pair pivoted together intermediate their ends and each lever having a fixed pivotal connection with one frame and a pivoted and sliding connection with the other frame; an operating lever at each end pivoted to the lower frame between the pivotal and sliding connections of the crossed levers with the frame and having a link connecting it to the end of the lever which has a pivoted and sliding connection with the lower frame; stop means comprising a stop member on one of the crossed raising levers at each end, and a co-operating stop on the operating lever adjacent thereto to engage the member when the upper frame is raised; and the operating lever having a laterally extending plate for its pivotal connection with the link in which the pivot is offset rearwardly from the pivot of the lever itself so that the link pivot may be moved to one side or the other of a line joining the other end pivot of the link and the pivot of the lever to lock the lever in a position against the stop to hold the upper frame in non-collapsible raised position and against movement in either direction from which it can be lowered only by manually moving the operating lever, being limited by the link engaging the end of its sliding connection in one direction and the lever being held against the stop means in the other direction.

3. A studio couch construction in accordance with claim 2 in which the pivoted and sliding connection includes a slot and a pivot attached to a lever and movable therein and the locking means for the operating lever tends to lock it rearwardly against the said stop means so that the crossed frame supporting members are locked in raised position with their pivots at the ends of the slots for limiting the extending movement of the levers in one direction and are locked by the engagement of the operating members with the said stop means for limiting the movement of the crossed levers oppositely in the slot in a collapsing direction whereby the upper frames are held upward in fixed position against movement in either direction and can only be lowered by manual movement of the operating levers.
